UNITED STATES PATENT OFFICE.

LUIS ARNAVAT OLIVÉ, OF BARCELONA, SPAIN.

CLOSURE FOR ENVELOPES OR SIMILAR WRAPPERS.

1,427,165.

Specification of Letters Patent. Patented Aug. 29, 1922.

Application filed October 6, 1919. Serial No. 323,783.

To all whom it may concern:

Be it known that I, LUIS ARNAVAT OLIVÉ, a citizen of the United States of America, resident at Barcelona, Spain, and at present 5 in Habana, Cuba (whose post-office address is #96 Gervasio Street, Habana, Cuba), have invented certain new and useful Improvements in a Closure for Envelopes or 10 Similar Wrappers, of which the following is a specification.

This invention relates to envelopes or similar wrappers, and particularly to the envelopes used for holding correspondence, and one of its objects is to provide a safety closure for that kind of wrappers, which should not be liable to being opened once closed unless by tearing out the envelope or wrapper and thus showing its violation.

Another object of the invention is to provide 20 an envelope or similar wrapper wholly deprived of glue or paste and which is closed by means of a clasp of novel construction.

And another object of the invention is to 25 provide an envelope formed by a blank of paper or of any other similar material with parts that are bent and folded on each other, thus constituting a safety cover which prevents access to the correspondence or object 30 wrapped, once the same is closed, and which is of an extension not larger than that of the common envelope at present in use.

The invention is described with reference 35 to the figures of the annexed drawings, of which:

Fig. 1 is a plan view of the blank serving for forming the envelope or wrapper.

Fig. 2 is an elevation of the blank showing 40 raised up the central portion projecting from the lower portion of the back of the envelope and which carries the male piece of the sealing clasp.

Fig. 3 is an elevation view showing folded and engaged together the two portions projecting laterally from the back of the envelope and upwardly raised the upper flaps which are engaged by the male piece of the sealing clasp.

Fig. 4 is a view similar to that of Fig. 3, 50 but enlarged showing partially bent downwards the upper flaps which are united together by the male piece of the sealing clasp.

Fig. 5 is a transverse vertical section of

the envelope on line 5—5 of Fig. 4, showing the same position of the parts.

Fig. 6 is a front elevation of the envelope completely closed.

Fig. 7 is an enlarged transverse section of the envelope on line 7—7 of Fig. 6.

Fig. 8 is a horizontal section of the envelope on line 8—8 of Fig. 4.

Figs. 9, 10 and 11 are perspective detail views showing respectively a joining clip at the lower portion of the envelope, and the male and female pieces forming the sealing clasp of the envelope.

The closure forming the subject-matter of this invention is preferably applied to an envelope formed by a blank of paper or of any other similar material divided by folds and 70 cuts in the following portions: a back 1, a central portion 2 projecting from the lower part of the back, a flap 3 projecting from the lower part of said central portion 2, a flap 4 projecting from the upper part of the back 75 1, lateral portions 5 and 6 projecting laterally from the back 1 and which constitute the front portion of the envelope, side flaps 7 and 8 projecting respectively from said lateral portions 5 and 6, upper flaps 9 and 10 projecting respectively from said lateral portions 5 and 6, and lower flaps 11 and 12 projecting respectively from said side portions 5 and 6. Each one of the upper flaps 4, 9 and 10 has a small slot 13, 14 and 15 respectively which correspond to each other in horizontal alignment. The side portions 5 and 6 have near its outer side edge a semi-circular opening 16 and 17 respectively, which are horizontally aligned and correspond in like manner with similar openings 18 and 19 formed in the side flaps 7 and 8. The central portion 2 also presents a semi-circular opening 20 which is in vertical alignment with the slot 13 of the upper flap 85 4. And the lower flap 3 has a narrow and elongated horizontal opening 21 which is in vertical alignment with openings 20 and 13, and a small slot 3' in the same alignment.

By this blank the envelope is formed in 100 the following manner: The central portion 2 is raised up until placing same parallel to the back 1; then the side portions 5 and 6 are folded on portion 2, after having folded thereon the lower flaps 11 and 12, and said 105 side portions 5 and 6 are united together by

folding one inside. Flaps 7 and 8 are also folded, as shown in Fig. 8, and the folded flaps are secured by means of a clip 22 whose ends close inwards through the fold formed 5 by the side flaps 7 and 8 and through the central portion 2 as shown in Fig. 7. In these conditions the envelope is ready for receiving the correspondence or other object to be wrapped between the central portion 10 2 and the back 1, and in order to close same without the use of any glue or paste at all, it is proceeded to place thereon the sealing clasp which is formed by a male piece and a female piece which fit into each other 15 once they are placed in position. The male piece of the clasp consists in a metal T-shaped strip 23 from whose head lead divergently downward two flexible shanks 24 and 25 and the strip 23 is widened at its lower 20 end forming an extension 23' provided with two side perpendicular flanges 26 and 27 raised on the extension 23' and in the space formed between these flanges is lodged a flexible tongue 28 formed by a cut in the 25 same extension 23' and which normally is interiorly raised on the plane of said extension. The female piece of the clasp consists of a metal T-shaped strip 29 which is bent on itself at its head forming a fore 30 flange 30 by means of which it is held in place, and said strip 29 is lowerly widened being integral with a small case 31 closed at all its sides excepting above and below and which presents at its fore part a flexible 35 tongue 32 formed by a cut in said fore part and which is normally raised inwardly on the plane of said fore portion.

The male piece of the clasp is placed in position by passing the extension 23' and the 40 strip 23 through the registering small slots 13, 14, 15 and 3' of the upper flaps 5, 9 and 10 and of the lower flap 3, from outside to inside, as shown in Figs. 5 and 7, until being stopped by the head of strip 23, and then 45 the oblique shanks 24 and 25 are bent over the edge of the united flaps 4, 9, 10 and 3, riveting same on itself in two or three points 33, whereby the lower end of the strip 23 remains hanging from said flaps. The female 50 piece is placed by hanging it, inside the central portion 2, from the horizontal opening 21 through which is passed the pending flange 30 which is riveted on strip 23 in two or three points 34, and in this position the upper open portion of the small case 31 remains behind the registering openings 20, 16 and 17, 18 and 19 respectively of the central portion 2, side portions 5 and 6 and side flaps 7 and 8.

In order to close the envelope, it is only 60 necessary to pass the extension 23' of the male piece through the registering openings 20, 16 and 17, 18 and 19 and to insert said extension 23' inside the small case 31 of the female piece until the flexible tongue 28

may pass beyond the flexible tongue 32 to engage one another, as shown in Fig. 7 of the drawings.

Once the envelope is closed, it is impossible to pull out the flexible tongue 28 from the small box 31 of the female piece, because the depth of this small box is such that the tongue 28 is tightly inserted within same and since the fitting into one another of both pieces is out of sight within the envelope and the registering openings 2, 16 and 17, 18 and 19 are hidden by the upper flaps, it is very difficult to introduce through the same the point of any sharp instrument such as a pin, needle, etc., to force out the separation of both tongues 28 and 32, unless by tearing out or breaking off the edges of the upper flaps.

It is obvious that the upper flaps 3, 9 and 10 projecting from the central portion 2 and 85 of the lateral portions 5 and 6 can be eliminated, and in such case the female piece of the clasp is to be hung from the upper edge of the central portion 2, and at any rate the upper flap 4 could be made with an inward 90 fold at its outer edge so as to impart more strength to same and prevent it from being easily torn out.

What I claim is:

1. A clasp comprising a member having 95 a flexible central arm and a pair of side arms which converge to one end of the central arm, the opposite end of said central arm being widened, said widened end having side flanges and a locking tongue between and spaced from said side flanges, and a second member having attaching means and also having a casing to receive the widened end of the central arm of the first named member and a locking tongue in said 100 casing for engagement with the first named locking tongue.

2. An envelope having a doubled closing end, and a clasp comprising a member having a flexible central arm and a pair of side 110 arms which converge to one end of the central arm, the opposite end of said central arm being widened, said widened end having side flanges and a locking tongue between and spaced from said side flanges, said 115 member being secured to said doubled closing end of the envelope by said flexible arm, and a second member in the envelope, the side of the envelope next the doubled closing end having an opening, and the central 120 arm of the first named clasp member being inserted through said opening into the body of the envelope and its widened end being engaged with said second member, said second member having a casing to receive said 125 widened end of said arm and also having a locking tongue to coact with the first named locking tongue.

In witness whereof I affix my signature.

LUIS ARNAVAT OLIVÉ.
